UNITED STATES PATENT OFFICE.

HENRY C. MONTGOMERY, OF CHICAGO, ILLINOIS.

VALVE.

No. 834,395.

Specification of Letters Patent.

Patented Oct. 30, 1906.

Application filed August 25, 1905. Serial No. 275,798.

To all whom it may concern:

Be it known that I, HENRY C. MONTGOMERY, a citizen of the United States, residing at Chicago, in the county of Cook and State 5 of Illinois, have invented new and useful Improvements in Valves, of which the following is a specification.

This invention is a slow self-closing valve adapted to be used in places where it is desired that a certain quantity of liquid shall flow and then be stopped. It is particularly serviceable and intended for use in flushing water-closets by direct flow from the water-main.

15 The object of the invention is to form an improved valve of the kind which after being opened will close slowly and silently, the rate of closure being controlled by the difference in area between two heads of the 20 valve which are subjected to the water-pressure.

In the accompanying drawings, Figure 1 is a central vertical section of the valve. Fig. 2 is a central vertical section of the cylinders 25 in which the valve-piston and push-rod work.

Referring specifically to the drawings, 6 indicates a globular valve-casing having a water-inlet 7 at the bottom and an outlet 8 at the side. Extending across this casing is a 30 diaphragm 9, in which is screwed a cylinder 10, which is closed at the bottom, as at 11, and has two chambers of different sizes, the upper chamber, which is the larger, being indicated at 12, and the lower chamber at 13. 35 Opening into the upper chamber are a series of lateral ports 14, which are extended upwardly, as at 15, to form a passage of large capacity. These ports open below the diaphragm 9.

40 Within the cylinder 10 is a piston-valve 16, having at the top a head 17 and at the bottom a head 18. The area of the head 17 is greater than that of the head 18, and the latter fits snugly in the chamber 13, the passage 19 being provided to allow the water to get slowly under the valve when it is closing and also to escape when the valve is pushed down. The upper head of the piston has a packing-washer 20, held in place by a 45 screw 21.

50 Located above the cylinder 10 is a cylinder 23, the inner lower edge of which overhangs the chamber 12, as at 22, so as to form a water-tight joint with the piston when the latter is lifted. The cylinder 23 has a threaded

rib 24 extending around the same and is screwed into the top part of the casing and bears at its lower end upon the top of the cylinder 10. This cylinder 23 has ports 25 to allow the outflow of the water into the space above the diaphragm, and thus to the outlet.

The cap of the casing is indicated at 26, screwed into the top thereof. The push-rod 27 for opening the valve works through this 55 cap and has a piston 28, which fits in the cylinder 23 and on its upper end has a handle 29 for its operation.

In the operation of the valve the upward pressure of the water thereon normally lifts 70 it and holds it closed. To open it, the handle is pushed down, forcing the piston to the bottom of the cylinder 10. The water then flows in and up through the ports 14 and 15 and out through the ports 25 to the outlet. 75 The water gets under the head 17 and gradually under the head 18, and the piston thus lifts slowly until it is closed, after which it is held closed by the water-pressure until the next operation. As the water flows up 80 through the valve-opening it lifts the piston 28 and the valve-rod out of the way of the valve-piston. The by-passage 30 through the wall of the cylinder 23 allows the escape of any leakage through the piston 28 and 85 avoids necessity for packing between the rod 27 and the cap 26 or on the piston 28.

What I claim as new, and desire to secure by Letters Patent, is—

1. A valve comprising a casing, a cylinder 90 supported therein, and having inlet and outlet openings, a piston movable in the cylinder and constructed to close the outlet by pressure of the fluid, an upper cylinder supported in the casing, and a push-rod which 95 extends through the casing and has a piston in said upper cylinder which receives the pressure of the fluid when the valve is opened, and is arranged to bear at its end against the piston, to open the valve, when the rod is 100 pushed down.

2. A self-closing valve comprising a cylinder having an inlet and an outlet, a piston movable therein, and arranged to advance and close the outlet by the fluid-pressure, 105 and having means to delay its advance, another cylinder beyond said outlet and in line with the first-mentioned cylinder, and a push-rod movable against the piston, to push the same back, and having a piston in said other 110

cylinder arranged to receive the pressure of the fluid passing the outlet, to push the rod back from the piston.

3. A valve comprising a casing, a lower cylinder therein closed at its lower end and having an outlet-opening at its upper end and an inlet at the side, a valve - piston fitting loosely in the cylinder, an upper cylinder screwed into the casing against the top of the lower cylinder and having an overhanging edge at the said outlet-opening against which the piston seats, and also having outlet-ports, and a push-rod extending through the casing

and having a piston in the upper cylinder, and arranged to push against the valve-piston to open the same, the upper cylinder having a by-pass from the space above its piston.

In testimony whereof I have signed my name to this specification in the presence of 15 two subscribing witnesses.

HENRY C. MONTGOMERY.
